TOY AIRPLANE

Glenn W. Isgrig, Cincinnati, Ohio, assignor to
William C. Woellner, Cincinnati, Ohio

Application August 9, 1943, Serial No. 497,885

2 Claims. (Cl. 46—77)

This invention relates to toy airplanes.

An object of the invention is to provide a toy airplane which may be sold or otherwise distributed in a knocked down condition in card or sheet form. The device may be quickly and easily assembled by a child without requiring the use of tools of any kind.

Another object of the invention is to provide a toy airplane which is adapted to be suspended from a control member which in turn is adapted to be held in the hand of an operator.

A further object of the invention is to provide a device having the hereinabove described characteristics, wherein the control member and plane are so correlated that the plane may be remotely controlled from said control member and caused to simulate various flying maneuvers, such as banking, diving, climbing, landing and taking off.

Still another object of the invention is to provide a toy plane which is suspended, at three points, from a manually operable control member.

These and other objects are attained by the means described herein and as disclosed in the accompanying drawing, in which:

Fig. 1 is a plan view of a blank containing the various elements of the present device.

Fig. 2 is a perspective view of the plane and control members of Fig. 1 in an assembled relationship.

As disclosed in Fig. 1, the various component parts of the present device may be scored on or otherwise partially severed from a sheet of material, such as cardboard, or the like, for facilitating easy removal or separation of said parts from the sheet material without requiring the use of scissors, or other special tools.

The present device comprises, broadly speaking, a plane 6 and a plane control member 7 to which it is secured by means of flexible members 8, as disclosed in Fig. 2.

The plane comprises a fuselage or body portion 10, a wing or main plane 11 and a stabilizer plane 12. The fuselage may be provided with a centrally located, preferably arcuate, wing receptive slit 14 of a length substantially equal to the width of wing 11 between points A and B at opposite ends of median line 9. A stabilizer receptive slit 15 is provided adjacent the rear or tail end of the fuselage, said slit being of a length substantially equal to the distance between points C and D at opposite ends of median line 21 of stabilizer 12. A small hole or other opening is preferably provided through the fuselage at a location above and forwardly of slit 15.

The outline of the fuselage may be made to conform with the outline of a prototype plane, and to that end, suitable indicia denoted generally by the numerals 17, 18 and 19 may be printed or otherwise provided on the sides of the fuselage for causing it to resemble an actual plane.

Main wing 11 comprises a pair of integrally formed complementary portions 20, the overall length of which is a dimension in excess of the overall length of the fuselage. A pair of slits 21 are provided, one in each wing portion 20, said slits converging inwardly from the outer or forward edge 22 of the wing.

Stabilizer 12 comprises a pair of integrally formed complementary portions 23 disposed on opposite sides of median line 21. The forward edge 24 of the stabilizer is provided with a slot 25, whereas the rear edge 26 is provided with an indentation 27.

Control member 7 comprises a hand grip portion 28, and a crossbar 32. The hand grip portion is provided, adjacent its forward end with a slit 29 extending inwardly from and at substantial right angles with upper edge 30. A second slit 31 extending inwardly and rearwardly from the upper edge is likewise provided.

Crossbar 32 is provided with a pair of slits 33 which converge inwardly from upper edge 34. Lower edge 35 is provided with a short slit 36 located midway between the spaced ends 37 of the crossbar.

In the preferred embodiment of the invention the linear distance between slit 29 and the inner edge 38 of slit 31 is substantially equal to the linear distance between hole 16 of the fuselage and a line drawn through the inner ends 39 of inner slits 21. Likewise, the inner ends 40 of slits 33 are spaced apart by a dimension substantially equal to the linear distance between the inner ends 39 of inner slits 21.

The component parts of the plane and control member may be suitably set off from sheet 13 by scoring or the like, in such a manner as to facilitate a clean severance of the elements from the sheet material along their outer edges. The plane may be assembled by inserting the tip of wing 11 into slit 14 of the fuselage, and then sliding the wing relative to the fuselage until median line 9 is centered relative to the slit. In a similar manner stabilizer 12 may be introduced into slit 15 for centering the median line 21 relative to the slit. It will be understood that slot 25 will engage opposite faces of the fuselage at the forward end of slit 15.

Crossbar 32 may be secured to hand grip portion 28 by introducing the crossbar into slit 29 of the hand grip and for effecting engagement of slit 36 with slit 29.

Three lengths of flexible material, such as string, thread, elastic, or the like, denoted generally by the numerals 8 may be secured at their upper ends to slits 31 and 33 of the control member, and at their lower ends to slits 39 and hole 16 of the plane for securing the plane in spaced parallelism relative to the control member. In this manner the plane is suspended from the control member, whereby movement of the control member will be transmitted through flexible members 8 to the plane. By way of example, if the control member be inclined downwardly and tilted about its longitudinal axis for lowering one end of crossbar 37, the nose of the plane will be lowered relative to the tail and one wing will be disposed lower than the other for simulating the flight of a plane banking while in a dive.

It will be observed that the three point suspension of the plane from the control member provides a positive yet flexible connection whereby the plane may be caused to simulate the various flying maneuvers to which real planes are subjected. The flexible nature of members 8 imparts a realistic air borne motion to the plane, which though connected to the control member, is nevertheless effected by the air currents set up incident to passage of the plane through the air.

Hand grip 28 is normally disposed in spaced parallelism with fuselage 10, whereas crossbar 32

32 is normally disposed in spaced parallelism with wing 11.

It will be understood that various modifications and changes may be made in the structural details of the device such as substituting a closed ended slot in hand grip member 28 in lieu of the open ended slit 29, within the scope of the appended claims, without departing from the spirit of the invention.

10. What is claimed is:

1. In a device of the class described, the combination of a toy plane including a fuselage and a wing secured to and extending at substantial right angles therefrom, a control member substantially corresponding in shape with the shape of the plane and including a hand grip portion and a crossbar secured to and extending at substantial right angles therefrom, and flexible means interconnecting said plane and control member for suspending said plane in spaced parallelism from said member.

2. In a device of the class described, the combination of a toy plane including a fuselage and a wing secured to and extending at substantial right angles therefrom, a control member including a hand grip portion extending lengthwise of the fuselage, and a crossbar secured to the hand grip portion and extending lengthwise of the wing, and flexible means interconnecting said wings to said crossbar and the fuselage to said hand grip portion for providing a three point suspension of said plane from said control member.
